CLAIM

The ornamental design for a blender, as shown and described.

DESCRIPTION

FIG. 1 is a front perspective view of a blender, showing my new design;
 FIG. 2 is a front view thereof;
 FIG. 3 is a rear view thereof;
 FIG. 4 is a left side view thereof;
 FIG. 5 is a right side view thereof;
 FIG. 6 is a top view thereof; and,
 FIG. 7 is a bottom view thereof.

(Continued)

In the drawings, the broken lines depict portions of the blender that form no part of the claimed design.
